UNITED STATES PATENT OFFICE.

RICHARD B. FENTEM, OF NEWMAN, CALIFORNIA.

LAND-GAGE FOR PLOWS.

SPECIFICATION forming part of Letters Patent No. 629,156, dated July 18, 1899.

Application filed March 1, 1898. Serial No. 672,210. (No model.)

To all whom it may concern:

Be it known that I, RICHARD B. FENTEM, a citizen of the United States, residing at Newman, in the county of Stanislaus and State of California, have invented certain new and useful Improvements in Land-Gages for Plows; and I do hereby declare the following to be a full, clear, and exact description of said invention, such as will enable others skilled in the art to which it most nearly appertains to make, use, and practice the same.

This invention relates to improvements in plows, and more particularly to land-gages therefor; and it consists in the novel construction and arrangement of the various parts, as hereinafter described.

In the drawings, Figure 1 is a plan view of the invention as applied to a plow-frame of the gang-plow type, the frame of the plow being shown in dotted lines and partly cut away to accommodate the figures of the other drawings. Fig. 2 is a detail view of the running-gear, the draft-beam of the plow being shown in section. Fig. 3 is a rear elevation of the operating-lever. Fig. 4 is a side view of the operating-lever, showing the end of the connecting-rod attached thereto.

The present invention applies more particularly to that type of plow known as "gang-plows," wherein a number of plows are carried upon the same frame. The motive power, whether horse or engine, is for this class of implements much greater than that used for the ordinary single plow. The shifting of the land-gage is therefore much more difficult of accomplishment in this class of implements.

The spread in operating plows of the gang-plow type is much greater than in the single plow, and therefore the extent of the movement of the usual land-gage would be proportionally greater. It is to accommodate these necessities by providing a land-gage easy of adjustment under a heavy load and sensitive to a diminished movement that is the object of the present invention.

To facilitate the description of the invention with reference to the drawings, I will let the letter A designate the draft-bar, to which the motive power is attached. The attachment of the draft-bar is by means of the draft-chain B. The chain is attached to the contracted eyes A' A', which are of usual con-

struction, to permit the links of the chain to extend edgewise between the contracted sides of the loop, while preventing them passing between the same in a crosswise position.

The draft-bar A is elongated to throw the points of the attachment of the draft-chain toward the extreme ends of the draft-beam C. The draft-beam C forms a part of the frame of the plow and extends across the full spread of operation of the plows constituting the gang.

The frame shown in the drawings is preferably constructed from steel I-beams, and the front beam, called the "draft-beam," is provided on the rear side with a wooden facing C', which fits snugly within the channel between the flanges on that side of the beam. The wooden facing is secured in place upon the beam by means of the threaded studs C², which are extended through perforations in the wooden facing and the web of the beam C. The studs C² are welded or firmly attached to the metal rod C³, which constitutes in this invention a track for the operation of the land-gage. When the studs C² are inserted through the perforations in the wooden facing and the beam, as mentioned, the outer ends are provided with the nuts C⁴, which when set draw the studs, the rod, and the wooden facing snugly and firmly into position.

Upon the rod C³ the carriage D operates. The carriage D consists of the grooved wheels D' D', which are journaled in the ends of stirrups D² D². These are maintained separated by a spreader-bar D³, which is provided with perforations D⁴ for various adjustments for the separation of the stirrups and wheels. The forward end of the stirrups is clamped over the draft-bar A, perforations A² being provided in the draft-bar to accommodate different adjustments. They are secured in position upon the draft-bar by screw-threaded bolts and nuts A³. The bolts A³ are in pairs, so as to hold the stirrups rigidly and perpendicularly to the draft-bar.

When constructed as described thus far, the draft bar and chain are connected to the draft-beam through a carriage which is mounted upon a track to move from end to end upon the draft-beam. It is to control this movement and to lock the carriage in the desired positions to which it is moved that I have provided the lever E and the interme-

diate connections between the said lever and the carriage.

The lever E is pivotally mounted upon what is termed the "land-beam" of the plow, a continuous threaded bolt E' being provided to extend through a suitable perforation, with nuts set upon either side of the web of the land-beam and having a smooth portion of the said bolt extending beyond the threaded portion to form a pivot for the said lever. A cotter-pin is used to hold the lever upon the pivotal part of the bolt when the lever is in position. The lever is provided with a guide-bracket E², the end of which is depended to form a guide for the lever E in its operation over the detent-quadrant E³. The detent-quadrant is provided with a suitable number of perforations to receive the bolt of the latch E⁴. This construction may be altered for one in which the quadrant is provided with a toothed formation to receive the bolt E⁴. When the lever is moved to any desired position, the bolt E⁴ is sprung into engagement with the quadrant by means of the spring E⁵ through the connecting-rod E⁶. When it is desired to change the position of the lever, the handle E⁷ is grasped, compressing the spring E⁵ and raising the bolt E⁴ out of engagement. The lever is then free to be moved to the new position and therein locked.

The intermediate connections consist in the lever F, the forward end of which is pivotally connected to the spreader-bar D³ by means of a bolt F'. The free end of the lever F is connected to the lower end of the lever E by means of the connecting-rod F². The lever F is fulcrumed upon the end of the swinging arm F³, which is pivotally mounted upon the land-beam of the frame of the plow at F⁴. The lever F is provided with the perforations F⁵ for an adjustable connection of the free end of the arm F³ therewith. By means of this adjustment the length of the stroke of the forward end of the lever F is increased or diminished as the connection of the arm F³ is moved toward the free end of the lever F or toward the forward end. The forward end of the lever F is also constructed so as to be adjustable upon the spreader-bar D³, the perforations D⁵ being provided in the said bar for that purpose.

By means of the intermediate connections here described the carriage carrying the draft-bar A may be shifted from side to side upon the track C³ while under great pressure. By shifting the adjustment of the connection between the end of the arm F³ and the lever F the movement of the carriage may be increased or diminished or the power applied thereto increased or diminished, as desired.

In its operation the land-gage constructed as herein described is connected to the motive power through the draft-bar A. This is spread so that a slight movement in either direction will bring the entire strain upon the length of the draft-chain B, to which it is connected, and thereby direct the entire

strain to that side of the plow to which the draft-bar is shifted. It is by means of this arrangement that the land-gage is rendered sensitive to the smallest movement.

As before stated, the motive power applied to draw plows of this type is so great that the power applied to shift the land-gage is necessarily increased. To accomplish this by means of hand-power, the lever F and the swinging arm F³ have been provided. Further, by this construction the line of movement along the straight path of the track C³ is maintained without diminishing the power applied.

Having thus described this invention, what is claimed is—

1. In a device of the nature indicated, a frame having a draft-beam, a rod secured to said beam upon the inner side thereof, a draft-bar having a wheel provided with a groove receiving the rod, and means for moving the draft-bar and its wheel along said rod; substantially as described.

2. In a device of the nature indicated, a frame having a draft-beam, a rod upon the inner side of said draft-beam and secured thereto by studs upon the rod entering openings in the beam, a draft-bar having a wheel provided with a groove receiving the rod, and means for moving the draft-bar and its wheel along said rod; substantially as described.

3. In a device of the nature indicated, a frame having a draft-beam with flanges extending from its inner side, a facing fitting in the channel between said flanges, a rod upon the inner side of said facing, studs upon said rod passing through the facing and secured to the beam, a draft-bar having a wheel provided with a groove receiving the rod, and means for moving the draft-bar and its wheel along said rod; substantially as described.

4. In a device of the nature indicated, a frame having a draft-beam, a carriage laterally movable along said beam, means for so moving the carriage, and a draft-bar laterally adjustable upon said carriage; substantially as described.

5. A land-gage for plows consisting in a combination of a draft-bar to spread the hitching connections toward the lateral limits of the operation of the plow; with a carriage to which the draft-bar is connected adapted to track on the frame of the plow; a lever connected pivotally to the carriage and a lockable lever mounted on the frame of the plow; and a swinging arm pivotally connected to the plow-frame and said lever and forming the fulcrum for the said lever, substantially as described.

6. In a device of the nature indicated a frame having a draft-beam, a draft-bar having lateral movement along said beam, an operating-lever upon the frame, a swinging arm pivoted upon the frame to the side of the draft-bar, a lever fulcrumed upon said swinging arm and having one end in pivotal connection with the draft-bar, and a connecting-rod

between the operating-lever and the free end of the lever fulcrumed upon the swinging arm; substantially as described.

7. In a device of the nature indicated a frame having a draft-beam, a draft-bar having lateral movement along said beam, an operating-lever upon the frame, a swinging arm pivoted upon the frame to the side of the draft-bar, a lever adjustably fulcrumed upon said swinging arm and having one end in pivotal connection with the draft-bar, and connection between the operating-lever and the free end of the lever fulcrumed upon the swinging arm; substantially as described.

15 8. In a device of the nature indicated a frame having a draft-beam, a draft-bar hav-

ing lateral movement along said beam, an operating-lever upon the frame, a swinging arm pivoted upon the frame to the side of the draft-bar, a lever fulcrumed upon said swinging 20 arm and having one end in adjustable pivotal connection with the draft-bar, and connection between the operating-lever and the free end of the lever fulcrumed upon the swinging 25 arm; substantially as described.

In testimony whereof I have hereunto set my hand this 31st day of December, 1897.

RICHARD B. FENTEM.
